Primary Examiner — Amy C Wierenga(74) *Attorney, Agent, or Firm* — Foley & Lardner LLP**CLAIM**

We claim the ornamental design for a faucet, as shown and described.

DESCRIPTION

FIG. 1 is a top, front, right perspective view of the claimed design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines shown in the drawings illustrate portions of the faucet that form not part of the claim.

The faucet is shown with a symbolic break in its length. The appearance of any portion of the article between the break lines forms no part of the claimed design.
